PEA SHOOTER

Edwin W. Helberg, Chicago, and Vernon C.
Helberg, Evergreen Park, Ill.

Application September 26, 1945, Serial No. 618,658

5 Claims. (Cl. 124—12)

1

This invention relates in general to toys, and more particularly to those devices commonly known as pea shooters.

The ordinary and well known pea shooter consists simply of a tube, one end of which is placed in the mouth of the user, who customarily carries the peas or other missiles to be projected in his mouth. Such a toy presents danger to the user from two standpoints, first, he is apt, under excitement or other unusual conditions, to swallow one or more of the peas which he holds in his mouth, and secondly, in warfare games and the like where running is involved, the child may fall and incur serious injury from the end of the tube extending into his mouth.

The primary purpose of our present invention is to provide a toy which will protect the user from injury caused by running the tube into his mouth or down his throat.

Another object is to provide a toy of the character indicated, in which a quantity of the peas or similar missiles can be stored in a magazine which is embodied in the structure of the toy. The magazine which will hold a substantial number of missiles makes the carrying of such missiles in the user's mouth entirely unnecessary.

While our invention contemplates a magazine in which a substantial number of missiles may be stored for use and automatically delivered as they are successively expelled, it also provides for the feeding of the missiles into the device singly by hand, if for any reason the user should prefer that manner of loading.

Other features and many of the inherent advantages of our invention will be readily appreciated as the same becomes better understood by reference to the following description when considered in connection with the accompanying drawing.

Referring to the drawing,

Fig. 1 is a side elevation of a pea shooter embodying the principles of our invention;

Fig. 2 is a sectional view on the line 2—2 of Fig. 1;

Fig. 3 is a view similar to Fig. 1 with portions of the device shown in section;

Fig. 4 is a plan view of the device illustrated in Fig. 1; and

Fig. 5 is an enlarged fragmental sectional view similar to the disclosure of Fig. 3, but showing the flexing of the missile holding fingers when the user blows through the tube to expel a missile therefrom.

By reference to the drawing it will be observed that the device comprises a tube indicated gener-

2

ally by reference character 6 looped or coiled to provide a single convolution with the ends 7 and 8 of the tube disposed preferably in substantially a common plane and projecting in opposite directions. The tube, made of light metal, plastic or other suitable material, may be reversible, that is, the mouth may be applied to either end and the missile will be projected from the opposite end when the user blows forcibly into the tube. Preferably, however, one end is rolled back as indicated at 10 to provide a mouth piece, and the bore is slightly reduced to prevent the passage at that point of a missile approximating in size the diameter of the tube. Since the two ends of the tube are disposed substantially in a common plane, the effect is that of an ordinary straight tube. The over-all length of the device, however, is much less than that of a straight tube of equal length, so that the device can be readily carried wholly concealed in the user's pocket. Furthermore, since the end to which the mouth is applied extends only a short distance from the convolution of the tube, the convolution will prevent the end from being accidentally jammed down the user's throat or into his mouth in such a manner as to cause serious injury.

The inner wall of the tube is provided intermediate its ends, that is, at the bottom of the convolution, with an opening 9 through which the missiles to be projected by blowing are delivered into the tube. A magazine adapted to contain a substantial number of missiles and which obviates the carrying of such missiles in the user's mouth, comprises a cylindrical member 11 of metal, plastic or other suitable material, the upper end of which is notched as indicated at 12 (Fig. 2) to interlock with the tube 6, and its lower end is telescoped over the upper portion of a base 13 formed of rubber or similar elastically resilient material notched at its lower extremity, as indicated at 14, to straddle the lower portion of the tube convolution. By pressing downwardly upon the cylinder 11 the base 13 can be compressed sufficiently to permit the upper end of the magazine to be disengaged from the tube 6 and tilted sideways to permit the filling of the magazine through the open upper end. When filled or replenished, the magazine may be tilted back into the position shown in the drawings where it will be held by engagement of the notch 12 with the overlying tube under the pressure exerted by the resiliency of the base 13.

It will be noted that the side walls of the cylinder 11 are provided with perforations 15 overlapping the upper edges of the base 13 surround-

ed by the cylinder walls. These openings are of sufficient size to permit one of the missiles 16, such as peas, beans, or other pellets, to be inserted through the opening into the magazine. From Fig. 2 it will be observed that the upper margin of the base 13 is pressed inwardly by the insertion of a missile. After the missile has been introduced, the displaced margin will resume its normal position and prevent escape through the openings 15 of any of the missiles from the magazine.

For the purpose of holding a missile which has passed from the magazine into the tube so that such missile will not roll through the tube and be delivered into the mouth of the user, or become lost in the event the toy should be inverted, and for the further purpose of insuring that only one missile will be delivered into the tube before an ejection by blowing is performed, we have provided a plurality of holding fingers 17 formed by slitting the lower end of a tube 18 formed of light weight rubber or rubberized fabric possessing a slight degree of resiliency and substantial flexibility. From Fig. 3 it will be observed that one of the missiles 16 delivered by the magazine into the tube is held by the fingers 17 so that it will not become displaced by any movement of the tube, but will remain immediately beneath the throat of the magazine so as to prevent the delivery of any further missiles until the one already in the tube is discharged.

From Fig. 5 it will be apparent that when air is blown through the tube from left to right viewing this figure, the fingers at the right of the missile will be flexed so as to permit the projection of the missile from the tube, while those at the left will be flexed upwardly by the air stream to temporarily hold the superposed missiles from falling into the tube and at the same time to substantially close or at least obstruct the throat of the magazine to minimize the loss of air pressure from the tube upwardly through the magazine. The missile already in the tube will, therefore, be carried by the air pressure through the remainder of the tube and discharged at the end 7, which in the instance illustrated becomes the delivery end of the tube.

The curvature of the tube serves to increase to some extent the velocity of the missile being discharged over the velocity of a similar missile discharged by the same air pressure in a straight tube, for the reason that centrifugal force will cause both the missile and the impelling air to hug the outer wall of the tube, thereby concentrating the air pressure back of the missile so as to utilize to the maximum extent the effectiveness of the air stream.

It should be apparent from the foregoing that we have provided a pea shooter which embodies a tube of considerable length in a compact structure so designed that it cannot be swallowed or jammed into the user's throat. The tube is capable of use as a shooter without the magazine attachment. In such case the tube would preferably be imperforate from end to end. In the form here illustrated, however, the tube is equipped with a magazine adapted to contain a substantial number of missiles which are retained until projected in the intended manner, thus obviating any danger of swallowing such missiles. The magazine when positioned in the convolution of the tube is closed, so as to prevent

loss of missiles therefrom, but may be readily displaced at its upper end for refilling by simply forcing the magazine cylinder downwardly against the resiliency of the base 13 until its upper end is freed from the tube. The flexible holding fingers prevent loss of missiles, insure feeding of the missiles from the magazine one at a time only, and serve as a substantial closure or obstruction to prevent loss of air pressure from the tube through the magazine.

The structural details illustrated and described may obviously be varied within considerable limits without exceeding the scope of our invention as defined in the following claims.

We claim:

1. A pea shooter comprising an open ended tube in the form of a single convolution coil having its ends projecting in opposite directions.

2. A pea shooter comprising an open ended tube in the form of a single convolution coil having its ends projecting in opposite directions with the longitudinal axes of said projecting ends disposed substantially in a common plane.

3. A pea shooter comprising an open-ended tube coiled into a single convolution with its ends projecting in opposite directions, one end of said tube being folded back upon itself to provide a mouthpiece surrounding the tube.

4. A pea shooter comprising an open-ended tube coiled into a single convolution with its ends projecting in opposite directions at the top of the convolution and provided in the inner wall of the lower portion of the coil with an opening, a magazine extending diametrically within the coil and engaged at its ends therewith to frictionally hold the magazine against displacement, said magazine communicating with the interior of the coil through said opening and said magazine being provided with an opening through a side wall thereof for the loading of missiles into the magazine.

5. A pea shooter comprising an open-ended coiled tube having its open ends extending in opposite directions at the top of the coil and being provided at the bottom of the coil with an opening, a magazine positioned within the coil so as to communicate with the interior thereof through said opening, said magazine extending diametrically of the coil and being shaped for interlocking engagement with the coil whereby the magazine is retained against displacement.
